UNITED STATES PATENT OFFICE

2,000,547

SLEEPING CAR

Arthur H. Woodward, Winnetka, Ill.

Application March 26, 1929, Serial No. 349,976
Renewed October 17, 1932

20 Claims. (Cl. 105—315)

My invention relates to sleeping cars and its object is to provide an improved compartment car in which the passenger capacity is materially increased without increasing the overall size of the car. A further object is the provision of a generous number of individual or single rooms. Compartment cars at present in vogue are of two general types. The older type comprises a series of compartments each of which accommodates two, and some of them three, passengers. The newer type comprises a series of individual or single compartments. In either case, the number of passengers which can be accommodated in the car is so limited that the economic waste entailed makes traveling in them expensive, and to a great extent prohibitively so.

My invention contemplates a double deck arrangement, i. e., lower and upper rooms, and by combinations of double and single rooms, and arrangement of the beds therein, I am enabled to utilize the standard allotment of space most efficiently and to accommodate a sufficient number of passengers in one car to bring travel in them within the means of the average patron of sleeping cars.

My invention is illustrated in the accompanying drawings in which

Figure 1 is a plan view showing the lower deck, the length of the car being conveniently broken 30 and only one pair of compartments being shown in detail;

Figure 2 is a partial plan view of the upper deck, this view being in appropriate alignment with the corresponding plan of Figure 1, in order 35 to facilitate reading of the drawings;

Figure 3 is a vertical cross-sectional view taken on the plane of the line 3—3 of Figure 2;

Figure 4 is a vertical cross-sectional view taken on the plane of the line 4—4 of Figure 2;

40 The other figures show a modified arrangement.

Figure 5 is a partial plan view of the lower deck;

Figure 6 is a corresponding partial plan view 45 of the upper deck, this figure being placed in vertical alignment with Figure 5 in order to facilitate reading of the drawings; and

Figure 7 is a cross-sectional view on the plane of the line 7—7 of Figure 6.

50 The car, as a whole, is indicated at 8, comprising the side walls 24a and 24b and the usual end vestibules 9 and 10. Solely for convenience of reference, the side wall 24a will be referred to as the right wall and the side wall 24b as the left wall. The body of the car between the end walls

11 and 12, in which doors 13 and 14, respectively are provided, is divided into a series of compartments and an aisle, as will now be described. The main floor or deck is indicated at 15 and the compartments on that deck are the so-called lower compartments. 5

Running along one side of the car is the aisle 15', of small width relative to the width of the car. The lower compartments are indicated at 16 and 17. They are all of the same size and are identical except that half of them are the complement of the other half, i. e., compartment 16 is the complement of compartment 17, and the next compartment to the right is the same as compartment 16, the length of the car thus 10 comprising a series of pairs of compartments or double units. The cross dividing wall 18 is a permanent one and the cross dividing wall 19 may have in it a sliding partition 19a acting as a door to permit communication between the adjoining compartments. The bed 20 lies lengthwise of the room, at one side thereof, and crosswise of the car. The arrangement is such, as will be seen, that a space results at the inner end of the bed, and this space may be utilized 15 for a cabinet 21. The floor space of the compartment is indicated at 15a and, as shown, it is ample for the installation of permanent toilet facilities shown as comprising a toilet stool 22 and wash basin 22'. A loose chair 22a 20 affords a seat for the compartment, which seat may face in either direction for either direction of travel or may face directly out of the window, at the window sitting space in the compartment. The windows 23—23 are 25 appropriately placed in the side walls 24 of the car, in transverse alignment, those on one side being placed, as shown, to light the floor space and above the bed and those on the other side lighting the aisle. The lengthwise dividing 30 wall 25 is provided with suitable doors 26—26 leading to the floor space of each compartment. At the ends of the interior of the car suitable space 27—27 may be provided to afford proper connection between the aisle 15' and the doors 13 and 14 and to provide, on the side opposite the aisle, space for storage of linen and other equipment. 35

In this form of my invention all the lower rooms are single rooms. 50

The upper rooms are all double rooms and they extend from side to side of the car i. e., over the lower rooms and over the aisle. The transverse partitions 18 and 19 extend the height of the car and extend completely across the car 55

except that all of them are arched at 28 to leave the aisle, and at just sufficient height, and the partitions 18 are additionally cut to provide for the centrally located stair well. This well is 5 formed by the walls 29, 30 and 31 and the stair, within these walls, indicated at 32, leads up from the aisle to the upper deck. The upper deck is of multiple stage construction, having the floor portions 33 and the bed portions 34, the latter 10 portions being higher than the former portions to the extent of the appropriate height of a bed. The floor portions 33 are substantially co-extensive with the beds below and lie directly over them. The bed portions lie over the floor portions 15 below and the aisle. The result is that a person may stand comfortably wherever there is floor space, or in the aisle, below and, at the same time, a person may stand comfortably wherever there is floor space above.

20 The upper compartments are indicated at 35 and 36. As in the case of the compartments below, they are identical except that half of them are a complement of the other half, and they are arranged in units or pairs over the compartments below and extending, further, over the aisle.

25 Each of the upper compartments has a transverse bed 37 and a lengthwise bed 38, the latter lying over the aisle and being substantially of the width of the aisle. The former is of the 30 same size as the bed below but it lies, as will be seen, against the wall 19 instead of against the wall 18. The floor space 33 of the upper compartment is ample for the accommodation of toilet facilities such as the toilet stool 39 and 35 wash basin 39', and for the accommodation of an unattached chair, such as the chair 22a in each lower compartment. My improved arrangement providing for this chair, which may be faced in either direction at the window sitting 40 space in the upper and lower compartments, is a desirable feature because many sleeping car patrons refuse to ride backward during day travel. The windows for the upper compartment are in number and position the same as 45 those below, being placed at a height immediately above the bed. Oblique doors 40-40 are appropriately provided between the stair walls 29 and 30 and the dividing wall 18 in order to afford access from the stairs to the respective 50 rooms of the unit which that particular stair serves.

The space between the top of the bed and the ceiling of each compartment, either upper or lower, is more than sufficient for retiring comfortably, and wherever there is occasion to stand, there is more than sufficient room for that purpose. No more than the standard length, width and height of sleeping cars now in vogue is required, and thirty passengers may be accommodated in the ten double and ten single rooms which may be provided in a car of such standard size.

In the form of my invention illustrated in Figures 5, 6 and 7, I decrease the number of 65 double rooms and increase the number of single rooms, which may be more popular on some runs. The arrangement there shown accommodates thirty passengers in six double upper rooms, six single upper rooms and twelve single 70 lower rooms.

For convenience the same reference characters are used for analogous parts in the showing of this modification. The differences are as follows:

The rooms and beds below are slightly smaller 75 and, above, each unit comprises a single and a

double room. The double room above is substantially the same as the double room shown in Figure 2, while the single room above has a transverse bed lying over the aisle and partly over the floor space of the room below. The partitions 18 of the lower deck extend only to the upper deck and the mid-partition 18' between the rooms of each pair above is slightly offset as will be seen by comparison of Figures 5 and 6. This arrangement of pairs of upper rooms 35 and 36 is 10 repeated along the length of the car whereby the single rooms 35 and double rooms 36 occur alternately, i. e., a single room 35, a double room 36, a single room 35 and so on.

I claim:

1. In a sleeping car, a main floor and a two stage upper deck, an aisle and a series of compartments on said main floor, a bed in each of said compartments, and a series of compartments on said upper deck each extending over said 20 first named compartments and said aisle, the lower stages of said upper deck lying over said beds and the upper stages thereof lying over the open floor spaces below and said aisle, and beds disposed transversely and lengthwise of the car in 25 said upper compartments on the upper stages of said upper deck over said open floor spaces and aisle, and adjacent to and accessible from a portion of the lower stage of said upper deck.

2. In a sleeping car, a body divided into an 30 aisle and a series of compartments, a two stage upper deck roofing said aisle and said compartments, a bed in each of said compartments, said bed lying transverse of the car, the lower stages 35 of said upper deck lying over said beds and the upper stages thereof lying over the open floor spaces below, a pair of compartments on said upper deck over each pair of compartments below, one of each pair of upper compartments having a bed transverse of the car on an upper stage 40 of said deck over said aisle and partly over the floor space below, and the other of each pair of upper compartments having a lengthwise bed lying over the open floor space of the compartment 45 below, said beds in the upper compartments being adjacent to and accessible from a portion of the lower stage of said upper deck.

3. In a sleeping car, a car body having a lengthwise partition and a series of transverse partitions forming an aisle and a series of compartments, a bed in each of said compartments, and a two-stage upper deck, the lower stages of said upper deck lying over said beds and the upper stages thereof lying over said aisle and over the 55 floor spaces of said compartments, and beds disposed transversely and lengthwise of the car on said upper stages over said floor spaces and aisle said latter beds being adjacent to and accessible from a portion of the lower stage of said upper 60 deck.

4. In a sleeping car, a body divided into an aisle extending along one side of the body and a series of lower compartments between said aisle and the other side of the body, beds in said lower compartments, a multiple-stage upper deck roofing said aisle and said lower compartments and divided into upper compartments, the lower stages of said upper deck lying over said lower beds and the upper stages thereof lying over the 70 open floor spaces below, beds in a plurality of said upper compartments on an upper stage of said deck and extending transversely of the car, and beds in a plurality of said upper compartments extending lengthwise of the car and lying 75

over the aisle, said beds in the upper compartments being adjacent to and accessible from a portion of the lower stage of said upper deck.

the car, said beds in the upper compartments being adjacent to and accessible from a portion of the lower stage of said upper deck.

5. In a sleeping car, a body divided into an aisle extending along one side of the body and a series of lower compartments between said aisle and the other side of the body, beds in said lower compartments, a multiple-stage upper deck roofing said aisle and said lower compartments and divided into upper compartments, the lower stages of said upper deck lying over said lower beds and the upper stages thereof lying over the open floor spaces below, a plurality of said upper compartments each having a bed disposed transversely of the car on an upper stage of said deck and a bed disposed lengthwise of the car lying over said aisle, said beds in the upper compartments being adjacent to and accessible from a portion of the lower stage of said upper deck.

9. In a sleeping car, a body divided into an aisle extending along one side of the body and a series of lower compartments between said aisle and the other side of the body, beds in said lower compartments, a multiple-stage upper deck roofing said aisle and said lower compartments and divided into upper compartments, a plurality of 10 said upper compartments each having two beds therein, one extending transversely of the car on an upper stage of said deck and another extending lengthwise of the car, said beds in the upper compartments being adjacent to and accessible from a portion of the lower stage of said upper deck 15

portion of the lower stage of said upper deck.

20 6. In a sleeping car, a body divided into an aisle extending along one side of the body and a series of lower compartments between said aisle and the other side of the body, beds in said lower compartments, a multiple-stage upper deck roof-
25 ing said aisle and said lower compartments and divided into upper compartments, the lower stages of said upper deck lying over said lower beds and the upper stages thereof lying over the open floor spaces below, a plurality of said upper compartments each having two beds therein and a plurality of said upper compartments each having a single bed therein, said double bed and single bed compartments alternating along the length of the car, the two beds of said double bed compartments comprising a bed disposed transversely of the car on an upper stage of said deck and a bed disposed lengthwise of the car lying over said aisle, the beds in said upper compartments being adjacent to and accessible from
30 35 40 a portion of the lower stage of said upper deck.

10. In a sleeping car, a body divided into an aisle extending along only one side of the body and a series of lower compartments extending across the entire space from said aisle to the opposite side wall of the body, beds in said lower compartments, a multiple-stage upper deck roofing said lower compartments and said aisle and divided into upper compartments, the lower stages of said upper deck lying over said lower beds and the upper stages thereof lying over the open floor spaces below, a plurality of said upper compartments having beds extending lengthwise of the car and adjacent to and accessible from a portion of the lower stage of said upper deck.

45 7. In a sleeping car, a body divided into an aisle extending along one side of the body and a series of lower compartments between said aisle and the other side of the body, beds in said lower compartments, a multiple-stage upper deck roofing said aisle and said lower compartments and divided into upper compartments, the lower stages of said upper deck lying over said lower beds and the upper stages thereof lying over the open floor spaces below, a plurality of said upper compartments each having two beds therein and a plurality of said upper compartments each having a single bed therein, said double bed and single bed compartments alternating along the length of the car, the two beds of said double bed compartments comprising a bed disposed transversely of the car on an upper stage of said deck and a bed extending lengthwise of the car, said beds in the upper compartments being adjacent to and accessible from a portion of the lower stage of said upper deck.

11. In a sleeping car, a car body comprising a main floor and two side walls, a lengthwise dividing wall adjacent to one of said side walls and defining therewith a lengthwise aisle extending along one side of the car body, a plurality of transverse partitions extending from said lengthwise wall to the opposite side wall of the car body and defining a plurality of lower compartments, beds in said lower compartments, a multiple stage upper deck roofing said lower compartments and said aisle, transverse partitions extending from side wall to side wall of the car body above said upper deck and defining a plurality of upper compartments, each of said upper compartments having standing room space therein on lower stages of said upper deck, the lower stages of said upper deck lying over portions of the beds in said lower compartments and the upper stages thereof lying over portions of the open floor spaces below, beds on upper stages of said upper deck extending lengthwise of the car, beds on upper stages of said upper deck extending transversely of the car and lying partly over said aisle and partly over the open floor spaces of the lower compartments, the beds on said upper stages being adjacent to and accessible from a portion of the lower stage of said upper deck, and transversely extending stairs leading at spaced intervals from said aisle to said upper compartments, each of said stairs affording access to two upper compartments. 35 40 45 50 55 60

8. In a sleeping car, a body divided into an aisle extending along one side of the body and a series of lower compartments between said aisle and the other side of the body, beds in said lower compartments, a multiple-stage upper deck roofing said aisle and said lower compartments and divided into upper compartments, the lower stages of said upper deck lying over said lower beds and the upper stages thereof lying over the open floor spaces below, a plurality of said upper compartments each having two beds therein and a plurality of said upper compartments each having a single bed therein, said double bed and single bed compartments alternating along the length of

12. In a sleeping car, a car body comprising a main floor and two side walls, a lengthwise dividing wall adjacent to one of said side walls and defining therewith a lengthwise aisle extending along one side of the car body, a plurality of transverse partitions extending from said lengthwise wall to the opposite side wall of the car body and defining a plurality of lower compartments, beds in said lower compartments, a multiple stage upper deck roofing said lower compartments and said aisle, transverse partitions extending from side wall to side wall of the car body above said upper deck and defining 75

- a plurality of upper compartments, each of said upper compartments having standing room space therein on lower stages of said upper deck, the lower stages of said upper deck lying over portions of the beds in said lower compartments and the upper stages thereof lying over portions of the open floor spaces below, beds in a plurality of said upper compartments extending lengthwise of the car and adjacent to and accessible from a portion of the lower stage of said upper deck, and transversely extending stairs leading from said aisle to said upper deck, each of said stairways affording access to a pair of adjacent upper compartments. 5
16. In a sleeping car, a body divided into an aisle extending along only one side of the body and a series of lower compartments extending across the entire space from said aisle to the opposite side wall of the body, beds in said lower compartments, a multiple stage upper deck roofing said lower compartments and said aisle, transverse partitions extending from side wall to side wall of the car body above said upper deck and defining a plurality of upper compartments, the lower stages of said upper deck lying over portions of the beds in said lower compartments and the upper stages thereof lying over portions of the open floor spaces below, beds in a plurality of 10 upper compartments on upper stages of said upper deck and extending lengthwise of the car, said latter beds being adjacent to and accessible from a portion of the lower stage of said upper deck and windows opening into said upper compartments at opposite sides of the car. 15
17. In a sleeping car, a car body comprising a main floor and two side walls, a lengthwise dividing wall adjacent one of said side walls and defining therewith a lengthwise aisle extending 20 along one side of the car body, a plurality of transverse partitions extending from said lengthwise wall to the opposite side wall of the car body and defining a plurality of lower compartments, certain of said partitions comprising doors for establishing direct communication between adjacent lower compartments, doors opening from the aisle into said lower compartments, toilet seats in said lower compartments between 25 said latter doors and said latter partitions, beds in said lower compartments, a multiple stage upper deck roofing said lower compartments, transverse partitions dividing the space above said upper deck into a plurality of upper compartments, the lower stages of said upper deck lying over 30 portions of the beds in said lower compartments and the upper stages thereof lying over portions of the open floor spaces below, beds in said upper compartments on upper stages of said upper deck and adjacent to and accessible from a portion of the lower stage of said upper deck, and transversely extending stairs leading from said aisle to said upper compartments. 35
18. In a sleeping car, a car body comprising a main floor and two side walls, a lengthwise dividing wall adjacent to one of said side walls and defining therewith a lengthwise aisle extending 40 along one side of the car body, a plurality of transverse partitions extending from said lengthwise wall to the opposite side wall of the car body and defining a plurality of lower compartments, certain of said partitions comprising doors for establishing direct communication between adjacent lower compartments, doors opening from the aisle into said lower compartments, toilet seats in said lower compartments between 45 said latter doors and said latter partitions, beds in said lower compartments, a multiple stage upper deck roofing said lower compartments, transverse partitions dividing the space above said upper deck into a plurality of upper compartments, the lower stages of said upper deck lying over portions of the beds in said lower compartments and the upper stages thereof lying over portions of the open floor spaces below, beds in said upper compartments on upper stages of said upper deck and adjacent to and accessible from a portion of the lower stage of said upper deck, and transversely extending stairs leading from said aisle to said upper compartments. 50
19. In a sleeping car, a body divided into an aisle extending along only one side of the body, a plurality of transverse partitions extending from said aisle to the opposite side wall of the body and defining a series of lower compartments, certain of said partitions comprising doors for establishing direct communication between adjacent lower compartments, beds in said lower compartments, a multiple stage upper deck roofing said lower compartments and said aisle, transverse partitions dividing the space above said upper deck into a plurality of upper compartments, the lower stages of said upper deck lying over portions of the beds in said lower compartments and the upper stages thereof lying over portions of the open floor spaces below, beds in said upper compartments on upper stages of said upper deck and adjacent to and accessible from a portion of the lower stage of said upper deck, and transversely extending stairs leading from said aisle to said upper compartments. 55
20. In a sleeping car, a body divided into an aisle extending along only one side of the body, a plurality of transverse partitions extending from said aisle to the opposite side wall of the car body and defining a plurality of lower compartments, windows in said opposite side wall opening into said lower compartments, the floor space of each of said lower compartments being of full standing room height at the window and adapted 60 to receive a movable chair which can occupy different positions at the window, beds in said lower compartments, a multiple stage upper deck roofing said lower compartments, transverse partitions extending from said wall to side wall of the car body above said upper deck and defining a plurality of upper compartments, the lower stages of said upper deck lying over portions of the beds in said lower compartments and the upper stages thereof lying over portions of the open floor 65
21. In a sleeping car, a body divided into an aisle extending along only one side of the body, a plurality of transverse partitions extending from said aisle to the opposite side wall of the car body and defining a plurality of lower compartments, windows in said opposite side wall opening into said lower compartments, the floor space of each of said lower compartments being of full standing room height at the window and adapted 70 to receive a movable chair which can occupy different positions at the window, beds in said lower compartments, a multiple stage upper deck roofing said lower compartments, transverse partitions extending from said wall to side wall of the car body above said upper deck and defining a plurality of upper compartments, the lower stages of said upper deck lying over portions of the beds in said lower compartments and the upper stages thereof lying over portions of the open floor 75

spaces below, beds in said upper compartments adjacent to and accessible from a portion of the lower stage of said upper deck, and stairs leading from said aisle to said upper compartments.

- 5 19. In a sleeping car, a car body comprising a main floor, right and left side walls and a roof, a lengthwise dividing wall adjacent to said right side wall and defining therewith a side aisle extending along the right side of the car body, a plurality of transverse partitions extending from said lengthwise dividing wall to the left side wall of the car body and defining a series of lower compartments, doors leading from said side aisle into said lower compartments, beds in said lower compartments, a multiple stage upper deck extending over said lower compartments and over said aisle, transverse partitions dividing the space above said upper deck into a plurality of upper compartments, transversely extending stairways leading from said aisle to said upper deck, each of said stairways affording access to a pair of adjacent upper compartments, lower stages of said upper deck lying over portions of the beds in said lower compartments and including portions extending at a substantially uniform level from said lengthwise dividing wall to said left side wall on opposite sides of said stairways to provide a substantially horizontal floor level in each upper compartment extending from said lengthwise dividing wall to said left side wall, upper stages of said upper deck extending at a substantially uniform level from said lengthwise dividing wall to said left side wall over the standing room space of each lower compartment to provide head room greater than that of the average standing passenger extending from said lengthwise dividing wall to said left side wall in each lower compartment, beds in a plurality of said upper compartments on upper stages of said upper deck and extending transversely of the car, and beds in a plurality of said upper compartments on upper stages of said upper deck and extending longitudinally of the car, said beds in the upper compartments being adjacent to and accessible from a portion of the lower stage of said upper deck.
20. In a sleeping car, a car body comprising a main floor, right and left side walls and a roof, a lengthwise dividing wall adjacent to said right side wall and defining therewith a side aisle extending along the right side of the car body, a plurality of transverse partitions extending from

said lengthwise dividing wall to the left side wall of the car body and defining a series of lower compartments, doors leading from said side aisle into said lower compartments, beds in said lower compartments, a multiple stage upper deck extending over said lower compartments and over said aisle, transverse partitions dividing the space above said upper deck into a plurality of upper compartments, transversely extending stairways leading from said aisle to said upper deck, each of said stairways affording access to a pair of adjacent upper compartments, lower stages of said upper deck lying over portions of the beds in said lower compartments and including portions extending at a substantially uniform level from said lengthwise dividing wall to said left side wall on opposite sides of said stairways to provide a substantially horizontal floor level in each upper compartment extending from said lengthwise dividing wall to said left side wall, upper stages of said upper deck extending at a substantially uniform level from said lengthwise dividing wall to said left side wall over the standing room space of each lower compartment to provide head room greater than that of the average standing passenger extending from said lengthwise dividing wall to said left side wall in each lower compartment, beds in a plurality of said upper compartments on upper stages of said upper deck and extending transversely of the car, and beds in a plurality of said upper compartments on upper stages of said upper deck and extending longitudinally of the car, said beds in the upper compartments being adjacent to and accessible from a portion of the lower stage of said upper deck.

ARTHUR H. WOODWARD.
